METHOD OF MAKING GOLF CLUB SHAFTS

Robert H. Cowdery, Geneva, Ohio, assignor to
The American Fork & Hoe Company, Cleve-
land, Ohio, a corporation of Ohio

Original application October 25, 1934. Serial No.
749,890. Divided and this application May 9,
1935, Serial No. 20,651

15 Claims.

(CL. 205—8)

This invention relates to the improved method and means for efficiently making tubular metallic shafts for golf clubs and other sporting implements.

5 It is an object of this invention to provide an improved method which will produce a tubular metallic shaft for golf clubs and other sporting implements having improved flexure characteristics and increased resistance to breaking characteristics.

10 Another object is to provide an improved method which will economically produce a resilient tubular metallic shaft for golf clubs and other sporting implements of the varying diameter type formed to give an increased resistance to flexure in those portions of generally smaller diameter.

15 Another object is to provide an improved method for making a resilient metallic shaft for golf clubs and other sporting implements wherein the flexure strains developed in use will not become concentrated in the portion of smallest diameter.

20 Another object is to provide an improved method for making a shaft for golf clubs of the continuous tapering type having the smallest diameter in portions adjacent the hosel and formed to have increased resistance to flexure in those portions.

25 Another object is to provide a method and apparatus for making improved shafts for golf clubs and other sporting implements as set forth in the foregoing objects.

30 My invention is fully disclosed in the following description taken in connection with the accompanying drawings, in which:

35 Fig. 1 is an elevational view illustrating a golf club having a shaft produced by the method of my invention;

40 Fig. 2 is a fragmentary longitudinal sectional view of the shaft of Fig. 1 drawn to a larger scale;

45 Figs. 3, 4, 5 and 6 are cross-sectional views of the shaft produced by the method of my invention taken respectively from the planes 3, 4, 5 and 6 of Fig. 1 and drawn to a larger scale;

50 Figs. 7 and 8 are respectively top plan and side elevational views, partly in section, and with parts broken away to simplify the drawings, of a machine for performing drawing operations in the process of making a shaft produced by the method of my invention;

55 Figs. 9, 10 and 11 are fragmentary views to an enlarged scale further illustrating steps of process performed by the machine of Figs. 7 and 8;

Figs. 12A to 12G inclusive are diagrammatic views illustrating further die-drawing steps in the process of making a shaft according to the method of my invention;

Fig. 13 is a partly sectional view approximately 5 full size illustrating one of the steps of process of Figs. 12A to 12G;

Fig. 14 is a partly sectional view taken from the plane 14—14 of Fig. 13;

Fig. 15 is a view illustrating a modification 10 which I may employ of a mandrel drawing element illustrated in others of the figures;

Fig. 16 is a fragmentary view similar to a part of Fig. 2 but illustrating a modification resulting from employment of the mandrel of Fig. 15. 15

Referring to the drawings, I have shown at 1 a tubular metallic shaft of a golf club produced by the improved process of my invention. The shaft 1 is preferably tapered from a hand grip supporting portion 7 of largest diameter towards the 20 extreme lower end 4 of the shaft. The lower end portion 2 is in the preferred embodiment illustrated gradually tapered from a point above the hosel 3, indicated at 9, to the end 4 of the shaft, and is wedgingly fitted into a corresponding 25 tapering bore in the tubular hosel 3 and secured against displacement therefrom by a transverse pin 5.

The portions of the shaft indicated generally at 6 between the tapering head end portion 2 and 30 the hand grip supporting portion 7 are preferably tapered and in the embodiment illustrated, are step-tapered by the provision of short cylindrical sections 8—8 of successively smaller diameter proceeding toward the small end of the shaft. 35

Although, in the embodiment illustrated, the gradually tapered portion 2 is shown to be longer than any of the stepped sections 8—8, this is subject to variation, in different embodiments.

In the particular form illustrated, the portion 40 2 begins at the point 9 at the lower end of the lowermost stepped section 8, and, at a suitable distance below the point 9, for example as at 10, the wall is thickened inwardly, and this increased thickness is continued from the point 45 10 to the end 4 of the shaft. This inward thickening or increased wall thickness in the portion 2 is accomplished by a decrease in internal diameter below the point 10 (or by an increase of internal diameter above that point), the change 50 of diameter being gradually effected over a short distance such as $\frac{1}{16}$ " or $\frac{1}{8}$ " longitudinally of the shaft, the portion in which the change of diameter is effected being indicated between the lines 10a and 10b. The length of the internally 55

thickened portion is preferably such that such portion extends outwardly of the hosel 3 of the club head for a distance of two to five inches, and in the embodiment illustrated is taken to be 5 three inches.

Besides the increased wall thickness in the lower end of the shaft as described, the shaft walls are preferably gradually and progressively increased in thickness proceeding toward the 10 small end of the shaft. Figs. 4 and 3, respectively, illustrate the increase of wall thickness of the previously thickened portion 2 proceeding toward the small end thereof. Figs. 6 and 5, respectively, illustrate the increase of wall thickness 15 from the upper to the lower portions of the tapered portion 6. Thus, in the embodiment shown, the outside diameter of the shaft produced by the method of my invention is progressively decreased from the large to the small 20 end and both the relatively thin-walled portion 6 and the relatively thick-walled portion 2 increase in wall thickness proceeding toward the small end.

In the use of a golf club having a shaft made 25 according to the improved process of my invention as above described, the more abrupt flexure usually occurring in prior shafts close to the juncture of the head hosel and the shaft when striking a ball, and the reactive flexure 30 thereafter, will be distributed over a substantial length of the lower end portion of the shaft including the thick-walled portion described, and a portion of the less thickened portion just above it, and will not be concentrated in a small length 35 near the hosel, and the shaft in its portion of smallest diameter will bend on a relatively large so-called radius of curvature, reducing the 40 liability of the shaft to break in the small diameter portion just above the head even after long continued use; also, the increased so-called radius of curvature effected by the described construction effects a longer contact between the head and the struck ball, securing greater length of 45 flight and better direction.

45 In Figs. 7 to 14 inclusive, the apparatus and method by which I prefer to manufacture the shaft above described is illustrated.

At 11 is indicated the base of a drawing machine commonly known as a draw bench and 50 having an integral die 12 rigidly secured thereto, the die being provided with a hardened die pass 13. Tongs 14 having gripping jaws 15-15 are supported on a carriage 16 having wheels 17 reciprocable on rails 18-18 on the base 11. A 55 chain 19 is connected to the carriage and comprises a flight 20 which may be pulled toward the right as viewed in the drawings to retract the carriage and jaws 15, and a flight 21 running over a suitable sprocket wheel 22 which may be drawn 60 toward the right as viewed in the drawings to advance the carriage and tong jaws 15. Such draw benches are well known in this art and this simplified showing and description are deemed sufficient.

65 Associated with the draw bench may be any suitable means under the control of an operator to draw the carriage 16 toward the right or to advance it toward the left and stop it in any position.

70 At 23 is a mandrel support secured to the base 11 having in an upper portion an upwardly open notch 24. A mandrel 25 is provided on the end of a rod 26, the mandrel being adapted to be disposed in the die pass 23 with the rod 26 in the 75 notch 24. A collar 27 threaded on the rod 26

and secured in any adjusted position by a lock nut 28 engages the support 23 to position the mandrel 25. The shaft is made from a cylindrical tubular blank, and this is illustrated in the drawings at 30.

5 In the operation of the apparatus, a tubular blank has one end thereof formed into a nose by rolling, hammering, swaging or like operations to reduce it to a generally pointed shape as shown at 30, Figs. 7, 8 and 9. The mandrel rod 10 26 is then rocked to the dotted line position illustrated in Fig. 8, and the end of tube 29 opposite the nose is telescoped over the mandrel 25 and rod 26 and the nose end of the tube is then rocked downwardly and projected forwardly toward the right as viewed in the drawings through the die pass 13. The carriage 16 is advanced and the tong jaws 15 operated to grip the nose 30. The mandrel rod 26 is now withdrawn toward the left as viewed in the drawings, 15 taking up a position indicated generally in Fig. 9. Such a position may suitably be with the mandrel 25 six or more inches rearwardly of the die pass 13.

The carriage 16 is now operated to draw the 20 tube through the die pass and is of such size as to reduce the outside and inside diameters of the tube.

For a golf shaft, suitable dimensions for the 30 tube blank are an outside diameter of .645 of an inch with a wall thickness .024 of an inch. As the tube is drawn through the die, its outside diameter will suitably be reduced to .625 of an inch, and this operation may be performed without a change of wall thickness.

35 After a sufficient length such as a few inches of the tube has been drawn through the die pass 13, the mandrel 25 will have moved with the tube or may be moved by hand to telescope the end thereof into the die pass, the parts taking up the 40 position indicated in Figs. 7 and 8 but more particularly in Fig. 10.

The mandrel 25 will be drawn into the die pass and its position determined by the collar 27 on the mandrel rod 26. For the shaft under consideration, a diameter for the mandrel 25 is chosen so that it will forcibly increase the inside diameter of the tube to .595 of an inch, reducing the wall thickness to .015 of an inch. The tube is drawn toward the right through the die 50 for the rest of its length, leaving it with the dimensions just stated, the die pass 13 continuously reducing the outside diameter and the mandrel increasing the inside diameter.

The resultant tubular blank therefore has a 55 uniform outside diameter of .625 of an inch with a wall thickness of .024 of an inch over a short portion of its length and a wall thickness of .015 of an inch over the rest of the length, thus providing a short end portion of increased wall thickness, or inwardly thickened wall.

The blank thus formed is tapered by being projected endwise through drawing dies by steps of process illustrated generally in Figs. 12A to 12G. The end of the blank with the increased wall 65 thickness is pushed successively through reducing dies 31 to 37 inclusive to reduce the outside diameter thereof and correspondingly increase the wall thickness, the blank being forced through the successive dies over shorter and shorter 70 lengths of the tube, producing cylindrical stepped sections 38-38 of successively smaller diameter, and finally a relatively long cylindrical section 38 having the inwardly thickened wall.

One of the dies, such as the die 31, and a por- 75

tion of the tube being projected therethrough, is illustrated in Figs. 13 and 14.

The above described process of tapering the tube may be carried out by various forms of apparatus and for a more complete description of the method and a machine for performing it, reference may be had to the United States Letters Patent of R. H. Cowdery, 1,963,048, June 12, 1934, and 1,963,047, June 12, 1934.

10 The section 38 of smallest outside diameter produced by the last die 37, may be taper-drawn to gradually reduce its outside diameter by any suitable drawing method of apparatus, one form of which is illustrated and described in the patent 15 to J. L. Cassady, 1,957,388, May 1, 1934.

The tube may be formed from any suitable metal such as steel alloy susceptible of being hardened by heat treatment to render it resilient, tough and durable. Before starting the drawing 20 operations above described, such tube blanks may be annealed and the finished drawn tube may be hardened by well known processes.

After the tube blank has been operated upon by the apparatus of Figs. 7 and 8 and as illustrated in Figs. 9 to 11, to provide the portion of 25 inwardly thickened wall, the tube may be tapered with a gradual taper from end to end, instead of by the stepped taper illustrated and described above, by any suitable method and means, one 30 form of which is shown in the above-referred to Patent No. 1,957,388.

In some cases it may be desirable to effect the 35 relatively abrupt change of wall thickness by a succession of steps instead of by a single step as illustrated at 10 in Fig. 2. In such cases, the mandrel 25 may be formed with successive steps of 40 successively greater diameter as shown at 40, 41 and 42 for the mandrel 43 of Fig. 15. The first section 40 of the mandrel may initially be drawn 45 into a drawing position in the die and fixed in that position by stop devices 44 and 45 between the collar 27 and the mandrel support 23. After a short length of the tube has been drawn through the die with its wall thickness slightly 50 reduced by the mandrel portion 40, the stop device 44 may be removed whereupon the mandrel will be drawn into the die to effect the drawing operation on the slightly larger diameter portion 41; and following that, the device 45 may be removed so that the remainder of the drawing operation 55 will be performed on the mandrel portion 42 of largest diameter.

When such a mandrel is used, the portion of the tube in which the change is made from the 55 thick walled portion to the relatively thin walled portion will appear as in Fig. 16 wherein the relatively thick walled portion 2 is reduced to a portion of relatively thin wall at 46 by two stages 47 and 48 of successively thinner wall.

60 As an alternative means to cause the change of wall thickness to occur over any suitable longitudinal extent of the tube, the collar 27 threaded on the mandrel rod 26 may be turned while the drawing operation is being performed to allow 65 the mandrel 25 to gradually move to its final position of minimum wall thickness. In such cases the lock nut 28 may be omitted.

I have found in practice that a very desirable 70 degree of increased wall thickness at the small diameter end of the finished golf shaft is attained if the wall of the shaft at the portion 2 where it enters the hosel is 45% greater in thickness than the wall at the opposite end of the shaft, and that a part of this increased wall thickness may be 75 provided by inwardly thickening a portion of the

wall of the cylindrical blank and further increasing it by employing a suitable tapering machine and method as above described; or a tapering machine and method may be employed which of itself does not increase the wall thickness, and in such cases the portion of increased wall thickness may be provided solely by the bench drawing operation above described.

It will be noted that in the use of golf clubs and other sporting implements having tubular metallic shafts of varying diameter, the greatest flexure strain tends to occur at the portion, usually of least diameter, just above the hosel of the club head, with the result that the shaft after continued use may crystallize and break at that portion; but in use of a club having a shaft produced by the method of my invention, when striking a ball, the reactive recoil of the club head is accomplished on a very short radius.

It is also to be noted that by first drawing, 20 without tapering, the portion of the tubular blank that is to be later tapered, by then drawing the remainder of the tubular element to a smaller internal diameter, and by finally die-tapering the 25 portions with the smaller diameter, namely the portions first die-drawn, that the process of manufacturing golf clubs is much reduced, over the manufacturing cost when other methods are used.

It will be understood of course that my invention is in no sense limited to the production of a shaft having the dimensions of tube and shaft above set forth, and in other respects the embodiment of my invention illustrated and described may be modified without departing from 35 the spirit of my invention or sacrificing its advantages and within the scope of the appended claims.

This application is divisional of my copending application, Serial No. 749,890, filed October 25, 40 1934, for improvements in Golf club shafts and methods and means for making same.

I claim:

1. The method of making a shaft for golf clubs which includes die-drawing a tubular blank to 45 reduce its internal and external diameters over a portion of its length, die-drawing the remainder of the length of the blank to reduce its external diameter and increase its internal diameter beyond that of the first portion, then taper-drawing the blank to dispose the portion of greatest wall thickness in the small end of the shaft.

2. The method of making a shaft or rod for 50 sporting implements which includes die-drawing a tubular blank to reduce its internal and external diameters over a portion of its length, die-drawing the remainder of the length of the blank to 55 reduce its external diameter and increase its internal diameter beyond that of the first portion, then step-taper-drawing the blank to 60 dispose the portion of greatest wall thickness in the stepped section of least diameter.

3. The method of making a shaft or rod for 65 sporting implements which includes die-drawing a tubular blank to reduce its internal and external diameters over a portion of its length, die-drawing the remainder of the length of the blank to reduce its external diameter and increase its internal diameter beyond that of the first portion, then step-taper-drawing the blank to 70 dispose the portion of greatest wall thickness in the stepped section of least diameter, then gradually tapering the smallest diameter section.

4. The method of making a shaft for golf clubs 75 which includes die-drawing a tubular metallic

- blank to reduce its external and internal diameters substantially without increase of wall thickness over a portion of the blank length, then die-drawing the remainder of the length of the blank to reduce its external and internal diameters with a substantial decrease of wall thickness, then taper-drawing the tube to dispose the portion of greatest wall thickness in the small end of the tube.
5. The method of making a shaft for golf clubs which includes die-drawing a tubular metallic blank to reduce its external diameter substantially uniformly from end to end and to reduce the wall thickness over a portion of the length 10 by a greater amount than over the remainder of the length, then taper-drawing the tube to dispose the portion of greatest wall thickness in the small end of the tube.
6. The method of making a shaft for golf clubs which includes die-drawing a tubular metallic blank to reduce its external and internal diameters over a portion of its length with a predetermined resulting wall thickness, then die-drawing the remainder of the tube to reduce 15 its external and internal diameters with a predetermined thinner resulting wall thickness, then taper-drawing the tube to dispose the portion of greatest wall thickness in the small end of the tube.
7. The method of making a shaft for golf clubs which includes die drawing a tubular blank to reduce its internal and external diameters over a portion of its length and die-drawing the remainder of the length of the blank to reduce its 20 external diameter and increase its internal diameter beyond that of the first named portion, then taper-drawing the blanks to dispose the portion of greatest wall thickness in the small end of the shaft.
8. The method of making a shaft for golf clubs which includes die drawing a tubular blank to reduce its internal and external diameters over a portion of its length and die-drawing the remainder of the length of the blank to reduce its 25 external diameter and increase its internal diameter beyond that of the first portion, and step-taper-drawing the blank to dispose the portion of greatest wall thickness in the stepped section of least diameter.
9. The method of making a shaft for golf clubs which includes die drawing a tubular blank to reduce its internal and external diameters over a portion of its length, die-drawing the remainder of the length of the blank to reduce its external 30 diameter and increase its internal diameter beyond that of the first portion, then step-taper-drawing the blanks to dispose the portion of greatest wall thickness in the step section of least diameter, then gradually tapering the smallest diameter section.
10. The method of making a shaft for golf clubs which includes die-drawing a tubular metallic blank to reduce its external and internal diameters substantially without increase of wall 35 thickness over a portion of the blank length and then die-drawing the remainder of the length of the blank to reduce its external and internal diameters with a substantial decrease of wall thickness, then taper-drawing the tube to dispose the portion of greatest wall thickness in the small end of the tube.
11. The method of making a shaft for golf clubs which includes die-drawing a tubular metallic blank to reduce its external and internal 40 diameters over a portion of its length with a predetermined resulting wall thickness and then die-drawing the remainder of the length of the latter to reduce its external and internal diameters with a predetermined thinner resulting wall thickness, then taper-drawing the tube to dispose the portion of greatest wall thickness in the small end of the tube.
12. The method of making a tubular shaft for golf clubs which includes die-drawing a tubular blank to produce therein a wall thickness greater 45 over a portion of the tube length than over the remainder of the length, then die-drawing the blank to taper it with the portion of greatest wall thickness in the small end of the tube.
13. The method of making a tubular shaft for golf clubs or the like which includes die-drawing a cylindrical tubular blank to provide therein a wall thickness greater over a portion of its blank 50 length than over the remainder of the length while maintaining a cylindrical outer wall thereon, then die-drawing the blank to taper it with the portion of greatest wall thickness in the small end of the tube.
14. The method of making a shaft for a golf club which consists, in first die-drawing the portion disposed toward one end of a tubular body to a given external diameter and to a given internal diameter, die-drawing the remainder of said body to the same external diameter as that 55 of the said portion first mentioned and to an internal diameter greater than that of the said portion first mentioned, and thereafter taper-drawing the said portion first mentioned, the taper gauges of the outer and inner surfaces of 60 the said portion last mentioned being dissimilar, that of the inner surface being of a sharper taper gauge than the outer, whereby a wall is formed along said first mentioned portion that thickens toward the said end first mentioned.
15. The method of making a shaft for golf clubs which consists in first die-drawing the portion of a tubular body, disposed toward one end thereof, to a given external diameter and to a given internal diameter, die-drawing the remainder of said body to a given external diameter and to an internal diameter greater than that of the said portion first mentioned, and then step-taper-drawing the said portion first mentioned, whereby the thickness of the wall of said body 65 along different cross sections of the said portion tapered increases as the cross section approaches the said end first mentioned.

ROBERT H. COWDERY.
